UNITED STATES PATENT OFFICE.

HENRY ADAMS SPEAR, OF CHARLESTOWN, AND ALBION PARIS WIGHT, JR., OF NORTH ADAMS, MASSACHUSETTS, ASSIGNORS TO THEMSELVES, HARRIE C. BROWNELL, OF NEWTONVILLE, AND FRANK BROWNELL, OF NEWTON, MASSACHUSETTS.

SMOKE-CONSUMER FOR LOCOMOTIVES, STATIONARY BOILERS, FURNACES, AND STOVES.

SPECIFICATION forming part of Letters Patent No. 310,920, dated January 20, 1885.

Application filed May 10, 1884. (No model.)

To all whom it may concern:

Be it known that we, HENRY A. SPEAR, of Charlestown, Suffolk county, Massachusetts, and ALBION P. WIGHT Jr., of North Adams, 5 in the county of Berkshire and State of Massachusetts, have invented certain new and useful Improvements in Smoke-Consumers for Locomotives, Stationary Boilers, Stoves, and Furnaces; and we do hereby declare that the 10 following is a full, clear, and exact description of the invention, which will enable others skilled in the art to which it appertains to make and use the same, reference being had to the accompanying drawings, and to letters 15 of reference marked thereon, which form a part of this specification.

Our invention relates to a special construction of parts, to effect a more perfect combustion, to consume the gases and smoke, and to 20 economize fuel; and it embraces as its leading features the admission of the air above instead of below the fuel in the fire-chamber, the carrying of the same downward through the ignited coal or fuel, to consume the gases and 25 smoke, and thereby intensify the heat, to consume the smoke and other products of combustion, and thence carrying the heated air into a chamber substantially air-tight, beneath the grate, and thence upward through a passage 30 leading to the boiler or to an outlet-pipe, as the case may be.

In the drawings our invention is shown in Figure 1 as applied to a stationary boiler, and in Figs. 2 and 3 as applied to a stove. Figs. 35 4 and 5 are sectional detail views of our invention as applied to a boiler. It will be evident, however, that it may also be applied to a locomotive, or to a furnace or stove for generating heat for any purpose desired.

40 Referring to Fig. 1, A represents the firebox of a stationary boiler; B, its grate, the bars b' of which are preferably made hollow or tubular to allow cold air or water to be run through them to keep them from melting or 45 being damaged by intense heat. These grate-bars may be of iron, or of stone or stoneware capable of withstanding a high degree of heat. These hollow grate-bars b' communicate with

each other by means of two similar hollow bars, b² b².

50 1 is an opening for the admission of air or water into one of the hollow bars b², and 2 is an outlet for the same. The water or air will then have a continuous flow from the entrance 1, through one of the hollow bars b² and grate-bars b', then through the other bar b², and finally out at the exit 2.

C is a bridge wall or partition, made of stone, brick, or iron, and separating the firebox or chamber A from a heat-passage, c', behind it, and it extends down some distance below the bottom of the grate, as shown at c''. Its function is to prevent the draft from passing from the grate and fuel directly to and through the outlet-flues of the boiler, and instead to throw or force it downward through the grate into the chamber E, which is directly under the grate, and the extension c'' of this bridge-wall confines this downward current until it shall have reached the lowermost edge 65 of this extension, and then, as indicated by the arrow, it passes upward through the passage c' to the boiler-flues c², and preferabl by the route indicated by the arrows, to utilize the heated air for the tubes to the best ad- 70 vantage.

75 The bridge-wall c c'', which we style a "water-leg," is made hollow to admit water or air to pass through it, in order to protect it from damage or melting from a high degree of heat. 80

85 3 is an opening near the top of the bridge-wall C for the admission of the water or air into said bridge-wall, and 4 is a cock or outlet for said water or air. As the air rises, it will be more convenient to use 4 as the inlet for air, when air is used, and 3 for the outlet, and vice versa when water is used.

D is a hinged slatted door having in or near it a slatted slide or air-inlet, serving as an adjustable valve for the admission of air above 90 the fuel to promote combustion. The coal is put in at this door.

95 F indicates the location or position of an air-tight ash-pan constituting the bottom of the chamber E.

G indicates the proper place for an exhaust-

blower, which may be employed, if desired, for the purpose of creating in some cases a stronger draft than would be otherwise induced through the air-inlet openings H of the chamber A, or through its slatted slide-door D, or through both.

If desired, air may be driven into the door D or inlets H by the agency of a pressure-blower or a steam-jet.

10 By our construction the fire pot or box A acts as a retort, in which the coal is coked, the gases extracted, and the cold air entering above and passing downward unites with the gases and promotes more complete combustion.

15 The same general features are employed and the same principle is involved and by a similar operation, in a stove or furnace or other heater, as illustrated in Fig. 2, in which like letters of reference indicate like parts, the 20 heat in this case passing out by means of a pipe, I, either to heating-pipes or to a chimney or otherwise, as circumstances may require. In this case there is no need of the bridge-wall, as the back of the stove, in connection with the opening therein below the 25 grate, where the pipe I is connected, being the only outlet, compels the draft to be in a downward direction through the body of the coal and through the bottom of the grate into 30 the lower chamber, E. The grate-bars may, however, be tubular, for the purpose above stated, and may be of any desired form or material.

In Fig. 3 the hollow grate-bars connect 35 with a pipe, j, running into the smoke-pipe, so that the same air which passes through the hollow grate shall serve to make a draft in this smoke-pipe. When the smoke-pipe connects with the stove-body at a point near the 40 bottom of the grate, as shown in this figure, it is best to put a piece of iron or metal, as shown at e'', serving the same duty as the extension e'' in Fig. 1—namely, to prevent the heat passing directly to the outlet-flue. This 45 deflector-extension may, as already stated, be hollow for the purposes already explained. When air only is to be discharged through the extension-pipe j, its outlet is preferably within the smoke-pipe I. When water only is to 50 pass through this extension-pipe j, this pipe should, as shown in dotted lines in Fig. 3, ex-

tend through or across such pipe, so as not to discharge within it. But both forms may be used in the same furnace or stove, a stop-cock being in such case employed at the bend of j 55 to direct the current either into or away from the smoke-pipe dependent on whether air or water is used.

In any stove embodying our improvements there may be a damper in the top to admit or 60 regulate the down current of air for supporting combustion, or a damper in the door above the grate, or both, the dampers being of any ordinary or well-known kind.

We claim—

1. In combination with a boiler - furnace having a downward draft, a hollow bridge-wall or partition, C, at the back of the fire-chamber, and not communicating with the boiler nor with the fire-box, and separating 70 it from the heat-passage behind, such wall being provided with an inlet and outlet, whereby a cool current either of air or water may be passed through it, as and for the purposes set forth.

2. In combination with a boiler - furnace having a downward draft, the hollow bridge-wall or partition C, to admit through it a current of air or water from the exterior, and provided with a hollow projection or extension, 80 e'', below the grate-bars, also adapted to admit through it a current of air or of water.

3. In a boiler-furnace having a downward draft, the combination of the hollow wall or partition C, its hollow extension e'', and the hollow 85 grate-bars, the partition, extension, and grate-bars being all adapted to admit through them a current or currents of air or water from the exterior.

4. In combination with a furnace provided 90 with hollow grate-bars adapted for passing through them a current or currents either of air or water, an extension-pipe, j, directly and continuously connecting with such hollow bars, and arranged in the smoke-pipe, as shown and 95 set forth.

HENRY ADAMS SPEAR.
